TELEPHONE SYSTEM

Edward S. Peterson, Elmwood Park, Ill., assignor to Associated Electric Laboratories, Inc., Chicago, Ill., a corporation of Delaware

Application January 6, 1938, Serial No. 183,591

41 Claims. (Cl. 179—31)

The present invention relates to telephone systems and has for one of its objects the provision of improvements in small automatic telephone systems adapted for use in providing intercar communication facilities between the various cars of a train or the like.

Systems suitable for the purpose specified conventionally comprise a plurality of telephone stations conveniently located in the various cars of the train, and a line comprising a plurality of talking conductors interconnecting the various stations. The utility of such a system resides primarily in the provision of facilities whereby passengers or porters may converse with the dining car and club car attendants for the purpose of placing orders for food and drink and for requesting other services. Obviously, there is no utility in providing such facilities for calls of a social nature. Moreover, the cost of providing a system for the purpose indicated and designed to handle more than one call at a time, would be prohibitive. It is highly desirable, therefore, to prevent the apparatus of the system from being used in connection with social calls since, otherwise, it might be tied up for extended periods of time by thoughtless passengers and to the inconvenience and disturbance of other passengers. Since ordinary conversations of a business nature are of short duration, one line interconnecting the several telephone stations is more than adequate for the provision of reasonably good service. With only one line available, however, the provision of suitable apparatus for preventing the line from being seized by a calling station when it is already busy becomes a practical necessity. For similar reasons, it is desirable to so arrange the system that dial tone indicating an idle condition of the line is given to a calling party when the line is in fact idle.

It is an object of the present invention, therefore, to provide an improved telephone system of the character briefly outlined above which is of economical and flexible arrangement, is positive and reliable in its operation even under the most adverse operating conditions, and is so arranged as to prevent connections from being established to certain of the telephone stations when calls thereto are initiated at certain of the other stations.

It is a further object of the invention to provide in a telephone system of the character described, an improved and exceedingly simple arrangement for preventing calls from effectively

being initiated when the line is engaged in a previously established connection.

It is a still further object of the invention to provide in a telephone system of the character described, an improved and exceedingly simple arrangement for automatically giving an audible signal to a calling party when the line is idle and when the calling party initiates a call from one station to a second station.

In the illustrated embodiment of the present invention, each of the plurality of telephone stations associated with the line comprises a telephone, an impulsing device, and a signal device and has associated therewith automatic, station selecting, switching apparatus of the impulse responsive type. Commonly associated with all of the stations is a dial tone source in the form of an undulating voltage generator connected to impress its output voltage between the talking conductors of the line. In accordance with one feature of the invention, a device in the form of a relay operative in response to the initiation of a call at one of the stations is provided for conditioning all of the automatic switches to respond to the operation of the impulsing device at the calling station and for rendering all of the switches non-responsive to the operation of the impulsing devices respectively provided at the other stations. This relay further functions to connect the telephone at the calling station across the talking conductors of the line, and to cause the operation of a second relay which is operative to initiate the operation of the dial tone generator, whereby an audible indication is given to the calling party that the line is idle. The switching apparatus associated with each of the telephone stations includes an automatic switch having operating positions individually corresponding to the various telephone stations, and further includes control apparatus responsive to the operation of the impulsing device provided at a calling station for causing the switch to operate to a desired position corresponding to a called station. Following the operation of the switches to a position corresponding to a particular called station, the switch at this station functions to complete a circuit for energizing the signal device thereat, and also to connect the telephone at this station across the talking conductors of the line. A further feature of the invention is directed to the provision of a device which responds to the first pulse transmitted from the impulsing device at a calling station to arrest the operation of the dial tone voltage generator.

In accordance with a further feature of the invention, the system is so arranged that calls initiated at certain of the stations, such, for example, as those provided in the sleeping cars, 5 may only be extended to predetermined ones of the other stations, as, for example, those provided in the club and dining cars, whereas calls initiated at the stations provided in the dining and club cars may be extended to any of the 10 other stations in the system. To this end, the switches associated with the stations arranged for limited call service each have a predetermined operating position intermediate the home position and certain of the operating positions 15 individually corresponding to the other stations. Also provided in individual association with the stations of this character is apparatus which responds to the operation of the associated switches to the predetermined operating position mentioned above to render all of the automatic switches non-responsive to further operation of the impulsing device provided at the associated station. By this arrangement, it is possible for a connection successfully to be completed between a station of the form noted and any station 20 corresponding to an operating position of the switches intermediate the home position thereof and the predetermined operating position noted. All of the other stations, namely, 25 those individually corresponding to the operating positions of the switches succeeding the predetermined switch operating position, cannot be reached when calls are initiated thereto from the stations arranged for limited call service.

30 Further features of the invention pertain to the particular arrangement of the circuit elements whereby the above-described services are attained.

The novel features believed to be characteristic 35 of the invention are set forth with particularity in the appended claims. The invention, both as to its organization and method of operation, together with further objects and advantages thereof, will best be understood by reference to the specification taken in connection 40 with the accompanying drawings wherein there is illustrated a telephone system having incorporated therein the features of the invention as briefly outlined above. In the drawings, Figure 1 illustrates a pair of telephone stations located in the same sleeping car of a Pullman train; Fig. 2 illustrates the automatic switching apparatus associated with the substation apparatus illustrated in Fig. 1; Fig. 3 diagrammatically illustrates the apparatus provided in two additional sleeping cars and the dining car of the train and also the substation apparatus provided at a station located in the club car of the train; and Fig. 4 illustrates the automatic switching equipment provided in the club car in association with the substation apparatus illustrated in Fig. 3, and also the equipment commonly associated with all of the telephone stations.

60 Referring now to the drawings, there is illustrated a telephone system for use on a Pullman train and comprising a plurality of telephone stations A, B, C, D, E, and F interconnected by a line 287, which line comprises a pair of talking conductors C286 and C284 and a common or control conductor C285. The enumerated stations are located in different cars of the train, and the line 287 is divided into sections individually extending throughout the length of the several cars which are provided with telephone facilities.

More specifically, the stations A and B are both located in one of the sleeping cars, the station C is located in a second sleeping car, the station D is located in the dining car, the station E in a third sleeping car, and the station F in the club car. The various line sections of the line 287 interconnecting these two stations are indicated as being connected by the sets of terminals 311, 312, 313 and 314, respectively. The line further comprises a fourth conductor divided into section C218, C218', etc., individually extending through the cars equipped for telephone service and joined together at the terminals 315, 316, 317, and 318, as indicated. Although each of the sleeping cars, aside from the first, is indicated as having embodied therein a single station, it is pointed out that each compartment of each sleeping car may be equipped with an outlet jack by way of which a portable telephone may be connected to have access to the line. Thus, the station B in reality consists of an outlet jack 148 adapted to accommodate the terminals of a multicontact plug 148 and having its contacts connected by way of the conductors forming a cable 268 to the switching apparatus provided in the car so that the portable telephone substation equipment may be connected to have access to the line 287. Additional outlet jacks individually located in the various other compartments of the sleeping car in which the station A is located may be provided, in which case the corresponding contacts of the several jacks are multiplied together.

The same equipment is provided at each of the telephone stations, that at the station A being illustrated as comprising a telephone hand set 155 including a receiver 160 and a transmitter 165, a dial actuated impulsing device 170, a signal device in the form of a buzzer 185, and a hook or cradle switch 180 located intermediate the cradle arms of the supporting member for the hand set 155 in the usual manner. Similarly, the apparatus provided at the station F comprises a hand set 360 including a transmitter 365 and a receiver 370, a dial actuated impulsing device 390, a signal device in the form of a buzzer 385, and a hook switch 380. Likewise the portable equipment illustrated as being located at the station B comprises a hand set 100, a dial actuated impulsing device 130, a signal device 115, and a hook switch 120.

Each of the transmitters and receivers embodied in the various hand sets may be of any standard commercial construction and for this reason these elements have been only schematically illustrated in the drawings. It is pointed out, however, that each of the transmitters 105, 165, 365, etc., is preferably of the self-powered type, such that the necessity of using an auxiliary current source for voice frequency current transmission is obviated. Several well-known transmitters of this type are commercially available. In brief, a transmitter of this form usually comprises a diaphragm which is connected by means of a sturdy but very light connecting rod to an armature balanced between the poles of an extremely powerful permanent magnet. In its operation and when sound waves impinge upon the diaphragm, the diaphragm vibrates in accordance with these waves to transmit the vibrations to the armature. The armature, in turn, vibrates and sets up variations in the magnetic lines of force, both in number and direction, causing an induced alternating voltage to be developed in the coil windings forming a part of

the magnetic field. The induced voltage thus generated varies in amplitude and frequency in accordance with the amplitude and intensity of the input sound waves.

Associated with each of the telephone stations is an automatic station selecting switch of the impulse responsive type, those provided in association with the stations A and F being illustrated generally at 260 and 440, respectively. Normally, each of the two enumerated switches is arranged to be operatively associated only with the indicated stations A and F, respectively. For the purpose of rendering the switch 260 available to the use of a portable telephone located at one of the compartment stations, as, for example, the station B, there is provided a relay R250 which is arranged to alter the circuit connections, in the manner pointed out in detail hereinafter, so that this switch may be controlled from any one of the extension stations. The automatic switches 260, 440, etc., are all of the well-known rotary type and are of identical mechanical construction. In brief, the switch 260 comprises three sets of bank contacts 261, 262 and 263, wipers 264, 265 and 266 respectively associated with the bank contact sets in the order of their enumeration, and means comprising a motor magnet 267 and a ratchet and pawl mechanism, not shown, for advancing the wipers from the home position of the switch, as illustrated in the drawings, to any one of a plurality of operating positions. Similarly, the automatic switch 440 comprises three sets of bank contacts 441, 442 and 443, wipers 444, 445 and 446 respectively associated with the bank contact sets in the order named, and means comprising a motor magnet 447 and a ratchet and pawl mechanism, not shown, for advancing the wipers from the home position of the switch, as illustrated in the drawings, to any one of a plurality of off-normal or operating positions. As pointed out more particularly hereinafter, certain of the plurality of off-normal or operating positions of the respective switches individually correspond to particular ones of the telephone stations and, thus, these switches are arranged to function as station selecting apparatus.

The control apparatus incorporated in or associated with each of the automatic switches provided in the respective sleeping cars may be identical with that illustrated in Fig. 2 in association with the station A, the extension station B, and any other extension stations located in the same car. In brief, the control apparatus illustrated in Fig. 2 comprises a relay R230 which is operative in response to the initiation of a call at the station A to condition all of the automatic switches embodied in the system to respond to the operation of the impulsing device 170 provided at the station A. More specifically, this relay is operative to prepare a series impulsing circuit including the windings of all of the impulsing relays R240, R330, R340, R350, R430, etc., the springs 171 of the impulsing device 170, the winding of R430, and the various sections of the line conductor C218, whereby each of the enumerated pulsing relays is energized and de-energized during each impulse dialed at the station A. This relay, namely R230, is further operative to connect the elements of the telephone hand set 155 across the talking conductors C284 and C286 of the line 287. In order to render the various automatic switches of the system non-responsive to the operation of the impulsing devices provided, respectively, at the stations other

than the station A, the relay R230 is further arranged to remove battery potential from the control conductor C285, thereby to prevent any of the relays corresponding to R230 and provided in the other cars from being operated in response to the initiation of calls at their respective associated stations. Since these corresponding relays are rendered inoperative following operation of R230, it will be apparent that the last-named relay also functions as a device for preventing the telephones at the other stations from being connected across the talking conductors of the line in response to the initiation of calls at the said other stations. The automatic switching apparatus associated with the station A further comprises the pulsing relay R240, a slow-to-release hold relay R220, a call limiting relay R210 and a slow-to-release line switching and buzzer control relay R200.

The automatic switching apparatus associated with the telephone stations C and E and provided, respectively, in the second and third sleeping cars may be identical with that just described. The automatic switching apparatus provided in the dining car and associated with the telephone station D differs from that embodied in the respective sleeping cars in that no control apparatus and more particularly no relay corresponding to R210, is included therein for limiting the stations which may be called from the station D. Specifically, the switching apparatus located in the dining car is identical with that illustrated in Figs. 3 and 4 and located in the club car.

Briefly described, the last-mentioned apparatus comprises, in addition to the automatic switch 440 and its associated line relay R430, a slow-to-release hold relay R410 and a line switching and buzzer control relay R400. The apparatus in this car further comprises a relay R420 which corresponds to the relay R230 provided in the first sleeping car and is operative to perform the same functions as are set forth above in the description pertaining to R230.

The various telephone stations have commonly associated therewith the common equipment 450 enclosed within the dotted area illustrated in Fig. 4. This equipment comprises a dial tone source or undulating voltage generator in the form of a self-controlled relay R460 connected to impress its output voltage by way of condensers 462 and 484 between the two talking conductors C286 and C284 of the line 287. For the purpose of initiating the operation of this generator, the relay R480 is provided, which relay includes a winding normally included in the above-mentioned impulsing circuit by way of which the various line relays are energized. This circuit is completed through the operation of a slow-to-operate relay R463 which responds to the operation of a common start relay R490. The last-named relay is arranged to be energized in series with any one of the relays R230, R420, etc., in response to the initiation of a call at any one of the stations respectively associated with the latter relays. The arrangement is such that the operation of the dial tone voltage generator is arrested when the first impulse is dialed at any calling station. To this end, there is also included in the common equipment 450 a slow-acting relay R470 which is arranged to be controlled by the start relay R490 and which functions to cause the restoration of R480 the first time the completed impulsing circuit is opened at the im-

pulsing device of a calling station. For the purpose of insuring the release of the various automatic switches following the operation thereof to complete a desired connection, there are provided two additional relays R486 and R495.

Current for energizing the various relays, the signal devices and the operating magnets embodied in the switching apparatus respectively associated with the several telephone stations is obtained from a common source which preferably comprises the storage battery conventionally embodied as standard equipment in the locomotive of the train. This source is usually connected to bus conductors which extend throughout the several cars of the train to supply current to the various lighting circuits and other auxiliary equipment. In order to facilitate a description of the circuits involved in the telephone system, the current source has not been illustrated in the drawings, but it is explained that the positive terminal of the source is connected to all circuit conductors indicated as terminating at ground, whereas the negative terminal of the source is connected to the various negative terminals illustrated in the drawings.

Considering now the operation of the system and assuming, for example, that a call is initiated at the station A located in the first sleeping car to the station F located in the club car, the automatic switching apparatus is conditioned for operation through the removal of the hand set 155 from its supporting cradle in the usual manner. When this operation is performed, the cradle switch 180 is caused to operate to its off-normal position. Assuming that the line is idle at the time the call is initiated, the operation of the cradle switch 180 results in the completion of a circuit for energizing the lower winding of R230 and the winding of R490 in series, this circuit extending from ground as applied to the conductor C185 by way of the switch springs 184, C275, the lower winding of R230, C285, RA472 and through the winding of R490 to battery. The relay R230, upon operating, completes, at RA235, a holding circuit for itself, this circuit extending from ground as applied to C185 by way of the switch springs 182 and 183, C274, RA235 and through the upper winding of R230 to battery. The relay R230 is so constructed that it closes the contacts associated with RA235 to complete the above-traced holding circuit for itself before the contacts associated with RA236 are closed. When the last-mentioned contacts are moved into engagement, the lower winding of R230 is short-circuited so that ground as extended to C275 is directly applied to the control conductor C285, thus removing from this conductor the predetermined potential, namely, battery potential, necessary to the energization of the relays corresponding to R230 and located in the other cars.

At RA231, the relay R230 prepares a circuit, traced hereinafter, for energizing R210 and, at RA234, it opens a point in the path normally short-circuiting the springs 171 of the impulsing device 170, thereby to render this device effective to control the pulsing relays corresponding to and including R480. At RA233, the relay R230 completes a path for connecting the transmitter and receiver of the telephone hand set 155 across the talking conductors C284 and C286 of the line 281, this path extending from the conductor C286 by way of the conductor C276, the transmitter 165 and the receiver 160 in parallel, C271 and RA233 to the opposite talking conductor C284.

The start relay R490 operates, when energized in series with the lower winding of R230, and is held operated following the operation of R230 through the application of ground potential directly to the control conductor C285. At RA492 and RC493, the relay R490 completes an obvious circuit for energizing the slow-to-operate relay R463, which latter relay operates, after an interval, to complete at RA465 and RA466 a path for short-circuiting the winding of R486 from ground on C285. At RA466, the relay R463 short circuits the armature RA472 to hold the start relay R490 operated after the slow-acting relay R470 operates. At RA467, the relay R463 completes an obvious circuit for energizing R495, which latter relay operates to complete, at RA496 and RC498 an obvious circuit for energizing R470. The relay R470 now operates to prepare, at RA471, a path for short-circuiting the winding of R486; to open, at RA472, a point in the original operating circuit for R490; and to prepare, at RA473, a holding circuit for itself. At RA491, the relay R490 prepares the above-mentioned impulsing circuit by way of which all of the line relays are energized in series. This circuit is completed at RA464 when R463 operates and is arranged to be controlled by the impulsing device 170 provided at the calling station and includes the winding of R488. More specifically, this circuit extends from ground as applied to C185 by way of C186, the impulsing springs 171, C273, RA251, the winding of R240, C218, the windings of R330, R340 and R350 in series, C218', RA422, the winding of R430, RA464, RA491, the winding of R480 and through the resistor 485 to battery. The conductor C186 is shown in dotted lines for the purpose of denoting a non-permanent connection. This conductor is in reality a jumper wire which is connected between ground and one of the impulsing springs of the dialing device provided at the permanent telephone station in the end car of the train of cars equipped for telephone service. The dotted portions of the conductors leading to the respective relays R330, R340 and R350 indicate that these conductors may be interrupted and include therein the contact springs of certain control relays, not shown. All of the enumerated line relays R240, R330, R340, R350 and R430 operate when the above-traced circuit is contemplated, to condition their respective associated switches to respond to the operation of the impulsing device 170 provided at the calling station. The relay R490 also operates, when energized over the above-traced circuit and before the operation of R470, to open, at RA481, a point in the path traced hereinafter for short-circuiting its own winding and to complete, at RA482, a circuit for initiating the operation of the relay R460 which forms the dial tone voltage generator. This last-mentioned circuit extends from ground at RA482 by way of the lower winding of R460 to battery.

When R460 operates, it completes, at RA481, an obvious path for connecting its upper and lower windings in series. These two windings are connected in opposition and, as a result, the relay restores to open the short-circuiting path and to permit its lower winding to again be sufficiently energized to cause its reoperation. Thus, R460 operates in the manner of a buzzer and, through its operation, impresses between the talking conductors C286 and C284 an undulating voltage which causes current to flow through the receiver 160 at the calling station of such a character that

an audible indication is given to the calling party that the line is idle.

When the line relay R240 associated with the switch 260 operates, it completes, at RA241 and RC243 an obvious circuit for energizing the hold relay R220, which latter relay, upon operating, prepares, at RA225, a holding circuit for R210, opens, at RA222 and RC223, a point in the release circuit for the magnet 267, and prepares, at RA222 and RC224, a circuit for energizing the switching relay R260 and the operating magnet 267 in parallel. In a similar manner, the hold relays provided in the switching equipment associated with the stations C, D, E and F are caused to operate. Thus, when R430, provided as an element of the switching apparatus located in the club car, operates, it completes, at RA431 and RC 433, an obvious circuit for energizing the hold relay R410. Since the club car station 20 is one of the stations arranged for unlimited call service, or arranged so that calls may successfully be completed to any of the other stations in the system, no relay corresponding to R210 is provided. Hence, the only function of R410 is to prepare, at RA412 and RC414, a point in the circuit, traced hereinafter, for energizing the switching relay R400 and the operating magnet 447 in parallel. Since the apparatus located in the dining car in association with the station D 25 is also arranged for unlimited call service and is in all respects identical to that illustrated in Fig. 4, the hold relay included in this apparatus performs only functions corresponding to those performed by R410. With the apparatus in this 30 condition, all of the automatic switches are conditioned to respond to the operation of the impulsive device 170 provided at the calling station. This device is now operated to transmit a plurality of impulses for causing the automatic switches to be driven to the operating position corresponding to the called station F.

More specifically, each time the impulse springs 171 are interrupted, the above-traced pulsing circuit, over which all of the line relays and R480 are energized, is interrupted. The resulting operation of the switching apparatus illustrated in Fig. 2 may be considered as exemplary of the operation of the other similar apparatus provided in the other sleeping cars, and for this reason, the operation of this apparatus will alone be considered in detail. Each time R240 restores, it completes, at RA241 and RC242, the above-mentioned circuit for energizing R200 and the operating magnet 267 in parallel. This circuit extends from ground at RA241 by way of RC242 and RA222 to RC224, where it divides, one branch extending by way of the winding of R200 to battery, and the other branch extending by way of C215 and the winding of the magnet 267 to battery. In response to its energization over the above-traced circuit, R200 operates to open, at RA204, a point in the path, traced hereinafter, for connecting the telephone hand set 155 across the talking conductors of the line and to prepare, at RA201 and RC203, a point in the circuit, traced hereinafter, for energizing R210. Due to its slow-to-release characteristic, the relay R200 remains operated for the duration of the series of impulses transmitted from the impulsive device 170. For the same reason, the relay R220 is held operated during impulsive. Each time the operating magnet 267 is energized and de-energized, it functions in cooperation with its associated ratchet and pawl mechanism to step its associated wipers 264 to 266, inclusive, one

step, so that at the conclusion of the dialing operation, these wipers stand in the operating position corresponding to the number of impulses making up the dialed number. In the present assumed case, the particular operating position of the switches corresponding to the called station F is the second off-normal position, as will be apparent from the wiring arrangement of the bank contact set 443 embodied in the switch 440. At the conclusion of the dialing operation, therefore, the wipers of the switch 260 remain standing in engagement with the respective third contacts of their respective associated contact sets.

Since all of the switches in the system and corresponding to the switch 260 are operated in synchronism during the dialing operation, it will be apparent that all of these switches will be caused to assume the operating position corresponding to the called station. Thus, when R430 restores during the first impulse dialed at the calling station, it completes, at RA431 and RC432, a circuit for energizing R400 and the operating magnet 447 in parallel, this circuit extending from ground at RA431 by way of RC432 and RA412 to RC414, where it divides, one branch extending by way of the winding of R400 to battery, and the other branch extending by way of C415 and the winding of the magnet 447 to battery. The relay R400 now operates to perform functions corresponding to those performed by R200, that is, to open, at RA404, a point in the path, traced below, for connecting the telephone hand set 360 across the talking conductors of the line and to open, at RA401, a point in the operating circuit for the buzzer 385. The two relays R400 and R410 remain energized throughout the impulsive operation due to their slow-to-release characteristics. Since the operating magnet 447 is energized and deenergized once during each impulse dialed at the calling station, the wipers 444, 445 and 446 of the switch 440 are caused to be advanced to the off-normal position which corresponds to the number of impulses making up the dialed series. In the present assumed case wherein the station F is the called station, these wipers are brought to rest in engagement with the respective third contacts of their respective associated sets. When the dialing operation is concluded, the springs 171 of the impulsive device 170 remain closed to hold 50 operated all of the line relays energized by way of the impulsive circuit.

Before describing the operation of the switching apparatus provided in the club car to complete a connection to the called station F, it is 55 pointed out that the operation of the relay R460, which functions as a dial tone current source, is arrested when the first pulse is transmitted from the impulsive device 170. Thus, when the above-traced impulsive circuit is opened, the relay R480 restores to complete, at RA481, a path including RA471 for short-circuiting its own winding. As thus short-circuited, no further operation of R480 can occur until R470 is restored. The last-mentioned relay is, however, held operated throughout the duration of the call and until the line is cleared. When R480 restores, it opens, at RA482, the previously traced circuit for energizing the lower winding of R460, thereby to stop the buzzer-like operation of the latter relay. At RA483, the relay R480, upon restoring, opens a point in the dial tone current path and clears the line of all impediments which might interfere with the transmission of voice fre- 75

quency currents over the talking conductors of the line.

Continuing now with the operation of the apparatus illustrated in Fig. 4, shortly after the conclusion of the series of impulses transmitted from the impulsing device 170 and with the wipers of the switch 440 standing in the second off-normal position, a circuit is completed for energizing the signal device 385 provided at the station F. More specifically, this circuit is completed upon the restoration of R400 and extends from ground as applied to C392 by way of the switch springs 381 and 382, the energizing winding of the device 385, C434, the third contact of the set 442, the switch wiper 445, RA411, RA401, RC402 and through the resistor 405 to battery. The device 387 now operates to give an audible indication that the station F is being called. With the wipers of the switch 440 standing in the second operating position and when R400 restores, a path is completed for connecting the transmitter 365 and the receiver 370 of the hand set 360 across the talking conductors C284 and C286 of the line 287. This path extends from the conductor C284 by way of RA404, the switch wiper 446, the third contact of the set 443, C435, and the receiver 370 and transmitter 365 in parallel to the opposite talking conductor C286. The talking loop between the calling and called stations is thus completed.

It is pointed out that the second off-normal or operating position of the various rotary switches corresponds only to the station F and, hence, the signal device 385 is the only one energized, and the telephone hand set 360 is the only hand set, other than that provided at the calling station, which is connected to the talking conductors of the line. To this end the respective third contacts of the two contact sets 442 and 443 are the only contacts of these sets which are wired, the remaining contacts of these sets, which individually correspond to stations other than the station F being left dead. The respective third contacts in the contact sets, corresponding to the sets 442 and 443 and included in the other rotary switches, are also left dead or unwired. It is for this reason that the signal device 385 is the only device of its kind which is energized and the telephone hand set 360 is the only hand set connected to the talking conductors of the line following operation of the switches to the second operating position. Had a digit comprising one or three impulses been dialed at the station A, a different station would have been signaled following the dialing operation, and the telephone hand set at this different station would alone have been connected across the talking conductors of the line.

When the call is answered at the station F through the removal of the hand set 360 from its supporting cradle in the usual manner, the cradle switch 388 is caused to operate to its off-normal position. As a consequence, the springs 381 and 382 are opened to interrupt a point in the above-traced circuit for energizing the signal device 385, the springs 382 and 383 are closed, and the springs 384 are closed. From the preceding description, it will be remembered that, ordinarily, closure of the springs 384 would result in the energization of R420. Due to the previous operation of R230, however, ground is present on the control conductor C285, so that the extension of ground from C392 to C439 occasioned by closure of the springs 384, only results in the

short-circuiting of the lower winding of R420. Hence, this relay remains deenergized.

No further operation of the switching apparatus occurs until such time as the connection is cleared out at the calling station. Thus, if the hand set 360 is returned to its cradle before the calling party hangs up, the only result is a re-completion of the circuit for energizing the signal device 385, all of the switches being held operated. When the hand set 155 at the calling station is thereafter replaced in its cradle, the holding circuit for R230 is interrupted at the switch springs 182 and 183, and ground is removed from C285. The start relay R498 is now energized in series with R486 over a circuit extending from ground at RA465 by way of the winding of R486, RA466 and the winding of R490 to battery. The relay R466 operates when energized over this circuit and interrupts at RA487 the circuit holding R463 operated. The relay 463, upon restoring, opens, at RA464, a point in the impulsing circuit and, at RA465 and RA466, points in the series circuit including R486 and R490. At RA467, the relay R463 opens the operating circuit for R495. With R495 deenergized, the weighted armature RA496 is released and starts vibrating alternately to make contact with its associated contacts RC497 and RC498. Due to the slow-to-release characteristic of R470, this relay stays operated so long as RA496 engages either of its two associated contacts. When, however, the amplitude of vibration of RA496 dies down so that it no longer engages either of its two associated contacts, R470 restores to open at RA471 the path short-circuiting the winding of R480 and to reprepare, at RA472, the circuit for energizing R490. When R490 falls back simultaneously with the restoration of R486 at opens, at RA491, a point in the series impulsing circuit over which all of the line relays are held operated and, at RA492, a further point in the operating circuit for R463.

When the various line relays fall back, the operating circuits for the respective associated hold relays are opened and circuits are prepared for energizing the various operating magnets embodied in the respective automatic switches to cause the wipers of the switches to be driven to the home position. Thus, when R240 restores, it prepares, at RA241 and RC242, a circuit for energizing the magnet 267 by way of the circuit-interrupting contacts associated with the armature 267'. At RA241 and RC243, the relay R240 interrupts the operating circuit for R220. The last-mentioned relay restores, after an interval, to complete the above-mentioned circuit for energizing the magnet 267, this circuit extending from ground at RA241 by way of RC242, RA222, RC223, C213, the wiper 264, the multiplied contacts of the set 261, C217, the armature 267' and through the winding of the magnet 267 to battery. Due to the circuit-interrupting action of the contacts associated with the armature 267', the magnet 267 is alternately energized and de-energized to drive the wipers 264, 265 and 266 of the switch 260 until they reach the home position of the switch. Since the first contact of the set 261 is not multiplied to the remaining contacts of this set, the above-traced circuit for energizing the magnet 267 is opened when the wiper 264 is stepped into engagement with its first contact. Thus, the switching apparatus associated with the station A is restored to normal and is in readiness for further use.

The operations which occur in the restoration

to normal of the switching apparatus provided in association with each of the other stations are quite similar to those just described in connection with the apparatus illustrated in Fig. 2.

5 Thus, when the line relay R430 incorporated in the switching apparatus associated with the station F restores, it opens, at RA431 and RC433, the operating circuit for R410 and prepares, at RA431 and RC432 a circuit for energizing the operating magnet 447 of the switch 440. This circuit is completed when R410 restores and extends from ground at RA431 by way of RC432, RA412, RC413, C406, the wiper 444, the multiplied contacts of the set 441, the armature 447' and the winding of the magnet 447 to battery. Due to the circuit-interrupting operation of the contacts associated with the armature 447', the operating magnet 447 is repeatedly energized and de-energized to drive the wipers of the switch 440 to the home position, or into engagement with the respective first contacts of their respective associated sets. Obviously, when this position is reached, the operating circuit for the magnet 447 is opened at the wiper 444 and its associated first contact.

10

15

20

25

If the calling party of the station A hangs up before the called party at the station F replaces his receiver in its cradle, the operated switches are automatically restored to normal in a manner similar to that just described. This is true even though ground as applied to C392 is extended by way of the switch springs 384 to C439 so long as the cradle switch 380 is operated to its off-normal position. Thus, when the hand set 155 is replaced in its cradle to cause the restoration of R230 ground is removed from the control conductor C285 so that a circuit is completed for energizing the lower winding of R420 in series with the winding of R490 and in parallel with R486. This circuit extends from ground on C439 by way of the lower winding of R420 to C285 where it divides, one branch extending by way of RA466 and the winding of R490 to battery and the other branch by way of the winding of R486 and RA465 to ground. Due to the relatively low resistance of the winding of R486, as compared to that of the lower winding of R420, the relay R420 does not operate when energized in parallel with R486. The relay R486, however, operates to open the operating circuit for R463, thereby to initiate the release of the apparatus in the manner pointed out above. It will be noted that when R463 restores, following the operation of R486, the operating circuit for the start relay R490 is open at two points, namely, RA466 and RA472, and can not be completed in response to the initiation of a call at one of the stations until such time as R470 restores.

The purpose of the arrangement described immediately above is to give the automatic switches sufficient time to restore completely to normal before they are conditioned to respond to impulses transmitted thereto during another call. More particularly, R486 operates when the calling party hangs up irrespective of whether or not a call is waiting to take the line. When R486 operates, R490 restores and, hence, the operating circuit for R490 and the impulsing circuit must be held open until R470 restores. Due to the continued energization of R470 occasioned by the vibration of RA496, however, R470 is held operated for a sufficient time interval to insure the full release of each of the automatic switches. There is thus eliminated any possibility of the automatic switches being started from an off-

normal position in response to the operation of an impulsing device provided at one of the stations.

As indicated above, the circuit arrangement of the switching apparatus is such that a call can only be initiated when the line 287 is idle. Thus, if the line 287 is busy at the time the call is initiated at the station A, the lower winding of R230, instead of being energized when the cradle switch 180 is operated to the off-normal position, is short-circuited. The short-circuiting path extends from ground at C185 by way of the switch springs 184, C275 and the lower winding of R230 back to ground as applied to the control conductor C285. Hence, R230 remains deenergized, no dial tone is received by the calling party, and the calling party is informed by the absence of such tone that the line is busy. Since, under the conditions stated, R230 does not operate, it is obvious that the attempted initiation of the call in no way interferes with the previously established connection responsible for the busy condition of the line. 5 10 15 20

As pointed out previously, when a plug terminating a portable telephone set is inserted in one of the extension jacks provided in the first sleeping car, the automatic switching equipment illustrated in Fig. 2 is conditioned to complete a connection to the telephone station thus formed or to respond to the operation of the equipment provided at the station to extend a connection to a desired called station. When, for example, the plug 148 terminating the portable telephone is inserted in the jack 140, the relay R250 is conditioned to operate to rearrange the circuit connections so that the impulse responsive switch 260 and its associated equipment are responsive to operation of the impulsing device 130.

Considering the operation of the apparatus to 40
complete a connection between the stations B and
F in response to a call initiated at the station B,
when the receiver at the station B is removed
from its cradle, the cradle switch 120 operates to
move the springs thereof to the positions indicated
in the drawings. In response to this operation, 45
a circuit is completed for energizing R250,
this circuit extending from ground as applied to
the jack spring 153 by way of the plug spring 141,
the switch springs 124, the plug spring 142, the 50
jack spring 149, C282 and through the winding of
R250 to battery. The relay R250, upon operating,
completes, at RA253, a circuit for energizing the
lower winding of R230 in series with the start 55
relay R490, this circuit being similar to that
traced previously but differing therefrom in that
it starts from ground at RA253, rather than from
ground as applied to C185. At RA252, the relay
560

R250 prepares a holding circuit for R230, this circuit being completed upon the operation of R230 and extending from ground at RA252 by way of RA235 and the upper winding of R230 to battery. At RA251, the relay R250 opens a point in the path normally provided for short-circuiting the impulsing springs 131 of the impulsing device 130. At RA254 and RC256, the relay R250 prepares a point in the path for connecting the transmitter and receiver of the hand set 103 across the talking conductors of the line 281. This path is completed upon the operation of R230 and extends from the conductor C284 by way of RA232, C278, the jack spring 153, the plug spring 143, the transmitter 105, and the receiver 110 in parallel, the switch springs 123 and 122, the plug spring 141, the jack spring 148', C281, 75

RA254 and RC256 to the opposite talking conductor C286. The operation of R230 also results in the connection of the hand set 155 across the talking conductors of the line 287 in the manner described previously. At RA236, the relay R239 completes a path for extending ground from RA253 directly to the control conductor C285, thereby to render the rotary switches, other than the switch 260, non-responsive to the operation of the impulsive devices respectively provided at all of the stations other than the stations A and B.

When the start relay R490 operates, following its energization in series with the lower winding of R238, it performs the functions described above, that is, it causes dial tone current to be transmitted through the receiver at the calling station B and completes the series impulsive circuit in which are energized the various line relays associated, respectively, with the several automatic switches. In this case, however, the impulsive circuit is arranged to be controlled by the impulsive device 130. Thus, the circuit now extends from ground as applied to C185 by way of C186, C272, the switch springs 171, C273, C280, the plug and jack springs 151 and 144, the impulsive springs 131, the plug and jack springs 146 and 152, C279, the series connected windings of R240, R363, R360, R359 and R430, RA464, RA491, the winding of R480 and through the resistor 435 to battery. From this point on, the operation of the apparatus to extend the connection to the called station F is identical with that described above, it being understood that in this case the various automatic switches respond to the operation of the impulsive device 130 rather than the impulsive device 170 provided at the station A. Also, the mode of releasing the connection after the conversation is terminated is substantially similar to that described in detail above. In this case, however, the release of the equipment after the calling party hangs up is initiated in response to the restoration of R250 and when the hand set 100 is restored to its cradle to open the switch springs 124 forming a part of the operating circuit for R250. When R250 restores, it opens, at RA253, a point in the path for applying ground to the control conductor C285, thereby to cause the restoration of R463 and the start relay R490, and opens, at RA252, a point in the holding circuit for R230, causing this relay to restore. The restoration of R463 results in the interruption of the impulsive circuit to cause the restoration of all of the line relays and their respective associated hold relays. When the line and hold relays restore, the various automatic switches are caused to be operated to their respective home positions in the manner pointed out above. If the calling party at the station B is the first to hang up, the automatic switches are restored in the manner described above.

As pointed out in the introductory portion of the specification, one feature of the present invention relates to the arrangement of the apparatus whereby any one of the telephones provided in any one of the sleeping cars may be called from the station located in the club car or from the station located in the dining car, but the equipment in the sleeping car stations can only successfully be operated to extend connections to the dining car station D or to the club car station F. To this end, the relay R210 is provided in the automatic switching apparatus located in the first sleeping car, which relay operates in response

to the operation of the switch 260 to a predetermined position and, upon operating, functions to short-circuit the impulsive springs of the impulsive device being operated, thereby to render all of the switches non-responsive to any further operation of this impulsive device. With the arrangement shown, this predetermined operating position of the automatic switches succeeds each of the two operating positions corresponding, respectively, to the dining car station D and the club car station F, and precedes the operating positions respectively corresponding to the several sleeping car stations. More particularly, the fourth off-normal position of the switch 260 and of the other switches 440, etc., is the predetermined position noted, which fourth off-normal position succeeds the first and second off-normal positions respectively corresponding to the dining car station D and the club car station F and is intermediate the home or first contact position of the switch and the fifth to twenty-fifth off-normal positions of the switch. These latter off-normal positions, or a portion thereof, individually correspond to the various stations, including the extension stations, provided in the several sleeping cars. If, therefore, a call is initiated at one of the sleeping car stations, as, for example, the station A, and the number of a sleeping car station, as, for example, the station C, is dialed at the calling station, the wipers of the several automatic switches are caused to be rotated in the exact manner set forth above until they occupy their respective fourth off-normal positions. Assuming that the call is initiated at the station A, when the wiper 265 is operated into engagement with its associated fifth contact, a circuit is completed for energizing R210, this circuit extending from ground at RC203 by way of RA201, RA221, C214, the switch wiper 265, the fifth contact of the set 262, C216, RA231 and through the upper winding of R210 to battery. The relay R210 immediately operates to short-circuit, at RA212, the springs 171 of the impulsive device 170, or to complete a bridging path for holding the various line relays operated, whereby further impulses dialed at the station A are prevented from causing any further operation of the several automatic switches. At RA211, the relay R210, upon operating, completes a holding circuit for itself, this circuit extending from ground at RA225 by way of RA211 and the lower winding of R210 to battery. By virtue of this holding circuit, R210 is maintained energized following the restoration of R200 at the conclusion of the dialing operation, thereby to prevent further actuation of the dialing device from inadvertently causing further operation of the several automatic switches. Since the respective fourth off-normal positions of the respective automatic switches do not correspond to any telephone station but rather are dead, it will be apparent that none of the telephone stations will be signaled following the completion of the dialing operation at the calling station A, and, hence, the calling party will receive no response.

The provision of the call limiting relays corresponding to and including the relay R210 and the circuits in which these relays are involved in no way interferes with the release of the apparatus when the call is cleared out at the calling station. On the contrary, the equipment is released and the various automatic switches restored to normal in the exact manner described above, it being pointed out that the call limiting relays restore

following the restoration of their respective associated hold relays. Thus, when R220, embodied in the control equipment associated with the switch 260, restores, it opens, at RA225, the holding circuit for R210. Since the operating circuit for the latter relay is previously opened through the restoration of R200 at the end of the dialing operation, R210 is caused to restore to normal. With the arrangement illustrated, no restriction is placed on the telephone stations D and F in regard to the initiation of calls to the sleeping car telephone stations. For this reason, no call restricting relay corresponding to R210 need be included in the switching apparatus located in the club car and illustrated in Fig. 4. The mode of operation of the system when a call to one of the sleeping car stations is initiated at the station F is substantially similar to that just described. In brief, when the hand set 360 is removed from its supporting cradle, the hook switch 380 is operated to its off-normal position to complete, at the springs 384, a circuit for energizing the lower winding of R420 in series with the winding of R490 and to prepare, at the springs 382 and 383, a holding circuit for R420. The operating circuit for R420 and R490 extends from ground as applied to C392 by way of the springs 384, C439, the lower winding of R420, C285, RA472 and through the winding of R490 to battery. The relay R420, upon operating, completes, at RA423, its holding circuit, opens, at RA422, a point in the path normally short-circuiting the springs 391 of the impulsive device 390, and completes, at RA424, a path for applying ground as extended to C439 directly to the control conductor C285, thereby to render all of the relays corresponding to R420 non-responsive to the initiation of calls at their respective associated stations. At RA421, the relay R420 completes a path for connecting the receiver and transmitter of the hand set 360 across the talking conductors C284 and C286 of the line 287. Specifically, this path extends from the conductor C284, by way of RA421, C435, and the transmitter 365 and the receiver 370 in parallel to the opposite talking conductor C286. When R490 operates, it functions, in the manner set forth above, to initiate the operation of the dial tone voltage generator, to complete the operating circuit for R463, and to prepare the impulsive circuit over which the various line relays are energized in series with each other and with R480. In this case, the springs 391 of the impulsive device 390 are arranged to control the impulsive circuit, this circuit extending from ground as applied to C185 by way of C186, C272, RA234, the windings of R240, R330, R340, and R350, etc., in series, C436, the impulsive springs 391, C437, the winding of R430, RA464, the winding of R480 and through the resistor 485 to battery. During impulsive, the operation of the several automatic switches conforms exactly to the operation as described above, the operating positions finally attained by these switches being dependent upon the number of impulses transmitted from the impulsive device 390. In this connection, it is pointed out that, if more than ten steps on the part of each switch are required to reach the operating position corresponding to the desired called station, two or more digits must necessarily be dialed at the calling station F to cause the switches to be operated to the required operating position. This is true for the reason that impulsive devices of the standard type are incapable of transmitting more than ten impulses for each actuation of the dial. If it be

assumed that the station A is being called from the station F, the impulsive device 390 will necessarily be actuated to break the impulsive circuit six times so that, at the conclusion of the dialing operation, the wipers of the switch 260 stand in their respective sixth off-normal positions. Shortly following the conclusion of the dialing operation, R200 restores to complete, at RA204, a path for connecting the transmitter 165 and the receiver 160 across the talking conductors of the line 287, this path extending from the talking conductor C284 by way of RA204, C283, the switch wiper 266, the seventh contact of the set 263, C271, and the transmitter 165 and the receiver 160 in parallel to the opposite talking conductor C276. At RA201 and RC202, the relay R200 completes a circuit for energizing the signal device 185, this circuit extending from ground on C185 by way of the springs 182 and 181, the winding of the device 185, C270, the sixth contact of the set 262, the switch wiper 265, C214, RA221, RA201, RC202 and through the resistor 205 to battery. The resulting operation of the signal device 185 gives an audible indication that the station A is being called. When the call is answered in the usual manner by lifting the hand set 160 from its cradle, the cradle switch 180 is operated to its off-normal position to interrupt, at the springs 181 and 182, the above-traced circuit for energizing the signal device 185. Following this operation, the apparatus is maintained in the condition described until the connection is cleared out at the calling station F. If the call as initiated at the station F is intended for the extension station B rather than the station A, the impulsive device 390 must necessarily be operated to open the impulsive circuit seven times instead of six, thereby to cause the switch 260 to be operated to its seventh operating position. In this case and when the stepping operation of the switch 260 is terminated at the conclusion of the dialing operation, a circuit is prepared for energizing the signaling device 115 at the station B and a path is prepared for connecting the transmitting and receiving elements of the hand set 100 across the conductors of the line circuit. The circuit for energizing the signal device 115 is completed when R200 restores and extends from ground on the jack spring 153 by way of the plug spring 147, the winding of the device 115, the springs 121 and 122, the springs 141 and 148, C281, RA254, RC255, the eighth contact of the set 262, the wiper 265, C214, RA221, RA201, RC202 and through the resistor 205 to battery. When the call is answered at the station B, this circuit is interrupted through the operation of the cradle switch 120 to open its springs 121 and 122. At the switch springs 124, a circuit is completed for energizing R250, this circuit extending from ground at the jack springs 153 by way of the plug spring 147, the spring 124, the plug spring 142, the jack spring 149, C282 and through the winding of R250 to battery. The resulting operation of R250 is without effect aside from the completion, at RA254 and RC256, of a path for connecting the elements of the hand set 100 across the talking conductors of the line. This path extends from the talking conductor C284 by way of RA204, C283, the switch wiper 266, the eighth contact of the set 263, C273, the jack and plug springs 150 and 143, the transmitter 105 and the receiver 110 in parallel, the switch springs 123 and 122, the plug and jack springs 141 and 148, 76

C281, RA254 and RC256 to the opposite talking conductor C286.

The release of a connection as established to either of the stations A and B on a call initiated at the station F is under the control of the calling party and is substantially similar to that described above with reference to the call initiated at the station A and resulting in a connection to the station F. Thus, when the hand set 360 is restored to its cradle after the called party hangs up, the holding circuit for R420 is interrupted at the springs 382 and 383 and the circuit over which the start relay R490 is held operated is interrupted at the springs 384. The resulting operation of R486 followed by the restoration of R463, R486 and R490 causes the common equipment 450 and the automatic switches provided in the respective cars to be restored to normal in the manner described above. The release of the apparatus when the called party at the station A or the station B is the last party to hang up is also similar to that described above with reference to the release of the connection as established between the stations 25 A and F on a call initiated at the station A. When the call initiated at the station F results in the establishing of a connection to the station B, the apparatus is only completely released when the hand set 100 is returned to its supporting cradle to operate the switch 120 to its normal position. When this is done, the springs 124 are opened to interrupt the above-traced operating circuit for R250 causing this relay to restore. When the hook switch 120 is returned to its normal position, a point is interrupted at the springs 122 and 123 in the path by way of which the elements of the hand set 100 are connected across the talking conductors of the line 287. Thus, this hand set is normally maintained disconnected from the line so that it will not interfere with other connections including the line. The remaining steps in the release of a connection as established to the station B on a call initiated at the station F will be readily apparent from 45 the preceding description.

While there has been described what is at present considered to be the preferred embodiment of the invention, it will be understood that various modifications may be made therein, and 50 it is contemplated to cover in the appended claims all such modifications as fall within the true spirit and scope of the invention.

I claim:

1. A telephone system comprising, in combination, a plurality of telephone stations each including an impulsive device and a signal device, automatic switches individually associated with at least a portion of said stations, each of said switches having operating positions individually corresponding to said stations, means responsive to the initiation of a call at one of said stations for conditioning the switch associated with a called one of said stations to respond to the operation of the impulsive device at the calling station, means also responsive to the initiation of said call for rendering all of said switches non-responsive to the operation of the impulsive devices at the other stations, means responsive to a predetermined operation of the impulsive device 60 at said calling station for causing the switch associated with said called station to operate to the position corresponding to said called station, and means automatically operative following the operation of said last-named switch to the position corresponding to said called station for caus- 70

ing the operation of the signal device at said called station.

2. A telephone system comprising, in combination, a plurality of telephone stations each including an impulsive device and a signal device, automatic switches individually associated with at least a portion of said stations, each of said switches having operating positions individually corresponding to said stations, means responsive to the initiation of a call at one of said stations 10 for conditioning all of said switches to respond to the operation of the impulsive device at the calling station, means also responsive to the initiation of said call for rendering all of said switches non-responsive to the operation of the impulsive devices at the other stations, means responsive to a predetermined operation of the impulsive device at said calling station for causing each of said switches to operate to the one position corresponding to a called one of said stations, a circuit for energizing the signal device at said called station, said circuit being prepared through the operation of the switch at said called station to said one position, and means automatically operative following the operation of said last-named switch to said one position for completing said circuit. 20

3. A telephone system comprising, in combination, a plurality of telephone stations each including an impulsive device and a signal device, automatic switches individually associated with at least a portion of said stations, each of said switches having operating positions individually corresponding to said stations, means responsive to the initiation of a call at one of said stations 30 for conditioning all of said switches to respond to the operation of the impulsive device at the calling station, means also responsive to the initiation of said call for rendering all of said switches non-responsive to the operation of the impulsive devices at the other stations, means responsive to a predetermined operation of the impulsive device at said calling station for causing each of said switches to operate to the one position corresponding to a called one of said stations 35 for individual circuits for energizing the signal devices at the respective stations, said circuits being selectively prepared through the operation of said switches and being so arranged that only the circuit for energizing the signal device at said called station is prepared through the operation of said switches to said one position, and means automatically operative following the operation of said switches to said one position for completing the circuit for energizing the signal device at said called station. 45

4. A telephone system comprising, in combination, a plurality of telephone stations each including an impulsive device, a line interconnecting said stations, automatic switches individually associated with at least a portion of said stations, each of said switches having operating positions individually corresponding to said stations, means responsive to the initiation of a call at one of said stations for conditioning the switch associated with a called one of said stations to respond to the operation of the impulsive device at the calling station, means also responsive to the initiation of said call for rendering all of said switches non-responsive to the operation of the impulsive devices at the other stations, and means responsive to a predetermined operation of the impulsive device at said calling station for causing the switch associated with said called station to operate to the one position corresponding to said called station 50

station, thereby to prepare a talking loop between said calling and called substations, said loop being completed when the call is answered at said called station.

5. A telephone system comprising, in combination, a plurality of telephone stations each including an impulsing device, a line interconnecting said stations, automatic switches individually associated with each of said stations, each of said

10 switches having operating positions individually corresponding to said stations, means responsive to the initiation of a call at one of said stations for conditioning the switch associated with a called one of said stations to respond to the operation of the impulsing device at the calling station,

15 means also responsive to the initiation of said call for rendering all of said switches non-responsive to the operation of the impulsing devices at the other stations, means responsive to a predetermined operation of the impulsing device associated with said calling station for causing the switch at said called station to operate to the one position corresponding to said called station, thereby to prepare a talking loop between

20 25 said calling and called stations, and means automatically operative following the operation of said last-named switch to said one position for further preparing said loop, said loop being completed when the call is answered at said called station.

30 6. A telephone system comprising, in combination, a plurality of stations each including a telephone and an impulsing device, a line interconnecting said stations and including a pair of talking conductors, automatic switches individually

35 associated with at least a portion of said stations, each of said switches having operating positions individually corresponding to said stations, means responsive to the initiation of a call at one of said stations for connecting the telephone at the calling station across the talking conductors of said

40 line and for conditioning all of said switches to respond to the operation of the impulsing device at said calling station, means also responsive to the initiation of said call for preventing the telephones at the other stations from being connected across said talking conductors in response to the initiation of calls at the corresponding stations and for rendering said switches non-responsive to the operation of the impulsing devices at said

45 other stations, means responsive to a predetermined operation of the impulsing device at said calling station for causing said switches to operate to the one position corresponding to a called one of said stations, and a path for connecting the telephone at the called station across

50 55 said talking conductors, said path being at least partially completed when the switch at said called station is operated to its said one position.

7. A telephone system comprising, in combination, a plurality of stations each including a telephone and an impulsing device, a line interconnecting said stations and including a pair of talking conductors, automatic switches individually associated with at least a portion of said stations, each of said switches having operating positions individually corresponding to said stations, means responsive to the initiation of a call at one of said stations for connecting the telephone at the calling station across the talking conductors of said line and for conditioning all of said switches to respond to the operation of the impulsing device at said calling station, means also responsive to the initiation of said call for preventing the telephones at the other stations from being connected across said talking conductors in response to the

initiation of calls at the corresponding stations and for rendering said switches non-responsive to the operation of the impulsing devices at said other stations, means responsive to a predetermined operation of the impulsing device at said calling station for causing said switches to operate to the one position corresponding to a called one of said stations, a path for connecting the telephone at the called station across said talking conductors, said path being partially completed when the switch at said called station is operated to its said one position, and means automatically operative following the operation of said last-named switch to its said one position for completing said path.

15 8. A telephone system comprising, in combination, a plurality of stations each including a telephone and an impulsing device, a line interconnecting said stations and including a pair of talking conductors, automatic switches individually associated with at least a portion of said

20 25 stations, each of said switches having operating positions individually corresponding to said stations, means responsive to the initiation of a call at one of said stations for connecting the telephone at the calling station across the talking conductors of said line and for conditioning all of said switches to respond to the operation of the impulsing device at said calling station,

30 35 means also responsive to the initiation of said call for preventing the telephones at the other stations from being connected across said talking conductors in response to the initiation of calls at the corresponding stations and for rendering said switches non-responsive to the operation of the impulsing devices at said other stations,

40 45 means responsive to a predetermined operation of the impulsing device at said calling station for causing said switches to operate to the one position corresponding to a called one of said stations, and circuit connections controlled by said switches for selectively connecting the respective telephones across said talking conductors independently of said second-named means, said circuit connections being so arranged that only the telephone at said called station is connected across said talking conductors in response to the operation of said switches to said one position.

50 55 9. A telephone system comprising, in combination, a plurality of telephone stations each including an impulsing device and a signal device, a line interconnecting said stations, automatic switches individually associated with at least a portion of said stations, each of said switches having operating positions individually corresponding to said stations, means responsive to the initiation of a call at one of said stations for preparing a talking loop between the calling station and a called station, said talking loop including said line, means responsive to the initiation of said call for conditioning the switch associated with the called station to respond to the operation of the impulsing device at said calling station,

60 65 means also responsive to the initiation of said call for rendering said switches non-responsive to the operation of the impulsing devices at the other stations, means responsive to a predetermined operation of the impulsing device at said calling station for causing the switch associated with said called station to operate to the one position corresponding to said called station, thereby partially to extend said talking loop to said called station, and means automatically operative following the operation of said last-named switch to said one position

for causing the operation of the signal device at said called station and for extending said talking loop to said called station.

10. A telephone system comprising, in combination, a plurality of stations each including a telephone, an impulsing device and a signal device, a line interconnecting said stations and including a pair of talking conductors, automatic switches individually associated with at least a portion of said stations, each of said switches having operating positions individually corresponding to said stations, means responsive to the initiation of a call at one of said stations for connecting the telephone at the calling station across said talking conductors and for conditioning all of said switches to respond to the operation of the impulsing device at said calling station, means also responsive to the initiation of said call for preventing the telephones at the other stations from being connected across said talking conductors in response to the initiation of calls at the corresponding stations and for rendering said switches non-responsive to the operation of the impulsing devices at said other stations, means responsive to a predetermined operation of the impulsing device at said calling station for causing said switches to operate to the one position corresponding to a called one of said stations, a path for connecting the telephone at the called station across said talking conductors, said path being partially completed when the switch at said called station is operated to its said one position, and means automatically operative following the operation of said switches to said one position for completing said path and for causing the operation of the signal device at said called station.

11. A telephone system comprising, in combination, a plurality of stations each including a telephone, an impulsing device and a signal device, a line interconnecting said stations and including a pair of talking conductors, automatic switches individually associated with at least a portion of said stations, each of said switches having operating positions individually corresponding to said stations, means responsive to the initiation of a call at one of said stations for connecting the telephone at the calling station across said talking conductors and for conditioning all of said switches to respond to the operation of the impulsing device at said calling station, means also responsive to the initiation of said call for preventing the telephones at the other stations from being connected across said talking conductors in response to the initiation of calls at the corresponding stations and for rendering said switches non-responsive to the operation of the impulsing devices at said other stations, means responsive to a predetermined operation of the impulsing device at said calling station for causing said switches to operate to the one position corresponding to a called one of said stations, individual circuits for energizing the signal devices at the respective stations, said circuits being selectively prepared through the operation of said switches and being so arranged that only the signal device at said called station is energized in response to the operation of said switches to said one position, and circuit connections controlled by said switches for selectively connecting the respective telephones across said talking conductors independently of said second-named means, said circuit connections being so arranged that only the telephone at said called station is connected across said talking conduct-

tors in response to the operation of said switches to said one position.

12. A telephone system comprising, in combination, a plurality of stations each including a telephone, an impulsing device and a signal device, a line interconnecting said stations and including a pair of talking conductors, automatic switches individually associated with at least a portion of said stations, each of said switches having operating positions individually corresponding to said stations, an undulating voltage generator connected to impress its output voltage between said talking conductors, means responsive to the initiation of a call at one of said stations for connecting the telephone at the calling station across said talking conductors and for initiating the operation of said generator, whereby an audible indication is given to the calling party that said line is idle, means responsive to the initiation of said call for conditioning all of said switches to respond to the operation of the impulsing device at said calling station, means also responsive to the initiation of said call for preventing the telephones at the other stations from being connected across said talking conductors in response to the initiation of calls at the corresponding stations and for rendering said switches non-responsive to the operation of the impulsing devices at said other stations, means responsive to a predetermined operation of the impulsing device at said calling station for arresting the operation of said generator and for causing said switches to operate to the one position corresponding to a called one of said stations, a path for connecting the telephone at the called station across said talking conductors, said path being partially completed when the switch at said called station is operated to its said one position, and means automatically operative following the operation of said switches to said one position for completing said path and for causing the operation of the signal device at said called station.

13. A telephone system comprising, in combination, a plurality of stations each including a telephone, an impulsing device and a signal device, a line interconnecting said stations and including a pair of talking conductors, automatic switches individually associated with at least a portion of said stations, each of said switches having operating positions individually corresponding to said stations, an undulating voltage generator connected to impress its output voltage between said talking conductors, means responsive to the initiation of a call at one of said stations for connecting the telephone at the calling station across said talking conductors and for initiating the operation of said generator, whereby an audible indication is given to the calling party that said line is idle, means responsive to the initiation of said call for conditioning all of said switches to respond to the operation of the impulsing device at said calling station, means also responsive to the initiation of said call for preventing the telephones at the other stations from being connected across said talking conductors in response to the initiation of calls at the corresponding stations and for rendering said switches non-responsive to the operation of the impulsing devices at said other stations, means responsive to a predetermined operation of the impulsing device at said calling station for arresting the operation of said generator and for causing said switches to operate to the one position corresponding to a called one

of said stations, individual circuits for energizing the signal devices at the respective stations, said circuits being selectively prepared through the operation of said switches and being so arranged that only the signal device at said called station is energized in response to the operation of said switches to said one position, and circuit connections controlled by said switches for selectively connecting the respective telephones across said talking conductors independently of said third-named means, said circuit connections being so arranged that only the telephone at said called station is connected across said talking conductors in response to the operation of said switches to said one position.

14. A telephone system comprising, in combination, a plurality of stations each including a telephone, an impulsing device and a signal device, a line interconnecting said stations and including a pair of talking conductors, automatic switches individually associated with at least a portion of said stations, each of said switches having a predetermined operating position and a plurality of additional operating positions individually corresponding to said stations, means responsive to the initiation of a call at one of said stations for connecting the telephone at the calling station across said talking conductors and for conditioning all of said switches to respond to the operation of the impulsing device at said calling station, means also responsive to the initiation of said call for preventing the telephones at the other stations from being connected across said talking conductors in response to the initiation of calls at the corresponding stations and for rendering said switches non-responsive to the operation of the impulsing device at said other stations, means responsive to a predetermined operation of the impulsing device at said calling station for causing said switches to operate to said predetermined position, means responsive to the operation of one of said switches to said predetermined position for rendering said switches non-responsive to further operation of the impulsing device at said calling station, whereby calls from said calling station to certain of the other stations are prevented, means responsive to a different predetermined operation of the impulsing device at said calling station for causing said switches to operate to the one position corresponding to a called one of said stations, a path for connecting the telephone at the called station across said talking conductors, said path being partially completed when the switch at said called station is operated to its said one position, and means automatically operative following the operation of said switches to said one position for completing said path and for causing the operation of the signal device at said called station.

15. A telephone system comprising, in combination, a plurality of stations each including a telephone, an impulsing device and a signal device, a line interconnecting said stations and including a pair of talking conductors, automatic switches individually associated with at least a portion of said stations, each of said switches having a predetermined operating position and a plurality of additional operating positions individually corresponding to said stations, means responsive to the initiation of a call at one of said stations for connecting the telephone at the calling station across said talking conductors and for conditioning all of said switches to respond to the operation of the impulsing device at said calling station, means also responsive to

the initiation of said call for preventing the telephones at the other stations from being connected across said talking conductors in response to the initiation of calls at the corresponding stations and for rendering said switches non-responsive to the operation of the impulsing device at said other stations, means responsive to impulses transmitted from the impulsing device at said calling station for causing said switches to operate to the one position corresponding to a called one of said stations or to said predetermined position depending upon the number of impulses transmitted from the impulsing device at said calling station, a path for connecting the telephone at the called station across said talking conductors, a circuit for energizing the signal device at said calling station, said path and said circuit only being completed in response to the operation of the switch associated with said called station to its said one position, and means responsive to the operation of one of said switches to said predetermined position for rendering said switches non-responsive to further impulses transmitted from said calling station, whereby calls from said calling station to certain of the other stations are prevented.

16. A telephone system comprising, in combination, a plurality of stations each including a telephone, an impulsing device and a signal device, a line interconnecting said stations and including a pair of talking conductors, automatic switches individually associated with at least a portion of said stations, each of said switches having a predetermined operating position and a plurality of additional operating positions individually corresponding to said stations, means responsive to the initiation of a call at one of said stations for connecting the telephone at the calling station across said talking conductors and for conditioning all of said switches to respond to the operation of the impulsing device at said calling station, means also responsive to the initiation of said call for preventing the telephones at the other stations from being connected across said talking conductors in response to the initiation of calls at the corresponding stations and for rendering said switches non-responsive to the operation of the impulsing device at said other stations, means responsive to impulses transmitted from the impulsing device at said calling station for causing said switches to operate to the one position corresponding to a called one of said stations or to said predetermined position depending upon the number of impulses transmitted from the impulsing device at said calling station, individual circuits for energizing the signal devices at the respective stations, said circuits being selectively prepared through the operation of said switches and being so arranged that only the signal device at said called station is energized in response to the operation of said switches to said one position, circuit connections controlled by said switches for selectively connecting the respective telephones across said talking conductors independently of said second-named means, said circuit connections being so arranged that only the telephone at said called station is connected across said talking conductors in response to the operation of said switches to said one position, and means responsive to the operation of one of said switches to said predetermined position for rendering said switches non-responsive to further impulses transmitted from

said calling station, whereby calls from said calling station to certain of the other stations are prevented.

17. A telephone system comprising, in combination, a plurality of stations each including a telephone, an impulsing device and a signal device, a line interconnecting said stations and including a pair of talking conductors, automatic switches individually associated with at least a portion of said stations, each of said switches having a predetermined operating position and a plurality of additional operating positions individually corresponding to said stations, an undulating voltage generator connected to impress its output voltage between said talking conductors, means responsive to the initiation of a call at one of said stations for connecting the telephone at the calling station across said talking conductors and for initiating the operation of said generator, whereby an audible indication is given to the calling party that said line is idle, means responsive to the initiation of said call for conditioning all of said switches to respond to the operation of the impulsing device at said calling station, means also responsive to the initiation of said call for preventing the telephones at the other stations from being connected across said talking conductors in response to the initiation of calls at the corresponding stations and for rendering said switches non-responsive to the operation of the impulsing devices at said other stations, means responsive to impulses transmitted from the impulsing device at said calling station for arresting the operation of said generator and for causing said switches to operate to the one position corresponding to a called one of said stations or to said predetermined position depending upon the number of impulses transmitted from the impulsing device at said calling station, a path for connecting the telephone at the called station across said talking conductors, a circuit for energizing the signal device at said called station, said path and said circuit only being completed in response to the operation of the switch associated with said called station to its said one position, and means responsive to the operation of one of said switches to said predetermined position for rendering said switches non-responsive to further impulses transmitted from said calling station, whereby calls from said calling station to certain of the other stations are prevented.

18. A telephone system comprising, in combination, a plurality of stations each including a telephone, an impulsing device and a signal device, a line interconnecting said stations and including a pair of talking conductors, automatic switches individually associated with at least a portion of said stations, each of said switches having a predetermined operating position and a plurality of additional operating positions individually corresponding to said stations, an undulating voltage generator connected to impress its output voltage between said talking conductors, means responsive to the initiation of a call at one of said stations for connecting the telephone at the calling station across said talking conductors and for initiating the operation of said generator, whereby an audible indication is given to the calling party that said line is idle, means responsive to the initiation of said call for conditioning all of said switches to respond to the operation of the impulsing device at said calling station, means also responsive to the initiation of said call for preventing the tele-

phones at the other stations from being connected across said talking conductors in response to the initiation of calls at the corresponding stations and for rendering said switches non-responsive to the operation of the impulsing devices at said other stations, means responsive to impulses transmitted from the impulsing device at said calling station for causing said switches to operate to the one position corresponding to a called one of said stations or to said predetermined position depending upon the number of impulses transmitted from the impulsing device at said calling station, a path for connecting the telephone at the called station across said talking conductors, a circuit for energizing the signal device at said called station, said path and said circuit being prepared when the switch associated with said called station is operated to its said one position, means automatically operative following the operation of said last-named switch to said one position for completing said path and said circuit, and means responsive to the operation of one of said switches to said predetermined position for rendering said switches non-responsive to further impulses transmitted from said calling station, whereby calls from said calling station to certain of the other stations are prevented.

19. In a telephone system, a pair of stations each including a telephone and an impulsing device, a line extending between said stations and including a pair of talking conductors, an impulse responsive switch associated with one of said stations and operative to a position corresponding to the other of said stations, an undulating voltage generator connected to impress its output voltage between said talking conductors, means responsive to the initiation of a call at the other of said stations for connecting the telephone thereat across said talking conductors and for initiating the operation of said generator, whereby the calling party is given an audible indication that said line is idle, means also responsive to the initiation of said call for conditioning said switch to respond to the operation of the impulsing device at the calling station, and means responsive to the operation of the impulsing device at the calling station for arresting the operation of said generator.

20. In a telephone system, a pair of stations each including a telephone and an impulsing device, a line extending between said stations and including a pair of talking conductors, an impulse responsive switch associated with one of said stations and operative to a position corresponding to the other of said stations, an undulating voltage generator connected to impress its output voltage between said talking conductors, means responsive to the initiation of a call at the other of said stations for connecting the telephone thereat across said talking conductors and for initiating the operation of said generator, whereby the calling party is given an audible indication that said line is idle, means also responsive to the initiation of said call for conditioning said switch to respond to impulses transmitted thereto from the impulsing device at the calling station, and means responsive to the first pulse transmitted from the impulsing device at said calling station for arresting the operation of said generator.

21. In a telephone system, a station including a telephone and an impulsing device, said telephone including a receiver, a station selecting impulse responsive switch associated with said

station, an undulating voltage generator, a circuit for energizing said receiver from said generator, means responsive to the initiation of a call at said station for completing said circuit and for initiating the operation of said generator, means also responsive to the initiation of a call at said station for conditioning said switch to respond to the operation of said impulsive device, and means responsive to the operation of said impulsive device for arresting the operation of said generator.

22. In a telephone system, a station including a telephone and an impulsive device, said telephone including a receiver, a station selecting impulse responsive switch associated with said station, an undulating voltage generator, a circuit for energizing said receiver from said generator, means responsive to the initiation of a call at said station for completing said circuit and for initiating the operation of said generator, means also responsive to the initiation of said call for conditioning said switch to respond to impulses transmitted thereto from said impulsive device, and means responsive to the first pulse transmitted from said impulsive device for arresting the operation of said generator.

23. In a telephone system, a station including a telephone and an impulsive device, said telephone including a receiver, a station selecting impulse responsive switch associated with said station, an undulating voltage generator, a circuit for energizing said receiver from said generator, a relay operative to initiate the operation of said generator, an operating circuit for said relay, a pair of relays operative in response to the initiation of a call at said station, one of said pair of relays being operative to complete said first-named circuit and to condition said switch to respond to impulses transmitted from said impulsive device, said one relay also being operative to connect the other of said pair of relays to be deenergized once during each impulse transmitted from said impulsive device, said other relay being operative to complete the operating circuit for said first-named relay, whereby said first-named relay is restored during the first impulse transmitted from said device, and a path for short-circuiting the winding of said first-named relay, said path being completed in response to the restoration of said first-named relay.

24. A telephone system comprising, in combination, a plurality of stations, a line interconnecting said stations, a relay associated with each of said stations, impulse responsive station selecting apparatus individually associated with said stations, each of said relays being operative to condition the associated station selecting apparatus to respond to impulses transmitted thereto from the corresponding station so long as said line is idle, and means controlled by each of said relays for preventing all of the other relays from operating.

25. A telephone system comprising, in combination, a plurality of stations, a line interconnecting said stations, said line including a control conductor, a relay associated with each of said stations, impulse responsive station selecting apparatus individually associated with said stations, each of said relays being operative to condition the associated station selecting apparatus to respond to impulses transmitted thereto from the corresponding station only when a predetermined potential is present on said control conductor, and means controlled by each of said re-

lays for removing said predetermined potential from said control conductors.

26. A telephone system comprising, in combination, a plurality of stations each including an impulsive device, a line interconnecting said stations, an automatic switch associated with each of said stations, each of said switches having a predetermined operating position and a plurality of additional operating positions individually corresponding to said stations, means responsive to the initiation of a call at one of said stations for conditioning said switches to respond to impulses transmitted from the impulsive device at the calling station, means responsive to impulses transmitted from the impulsive device at the calling station for causing said switches to operate to the position corresponding to a called one of said stations or to said predetermined position depending upon the number of impulses transmitted from the impulsive device at said calling station, and means responsive to the operation of one of said switches to said predetermined position for rendering said switches non-responsive to further impulses transmitted from the said impulsive device at said calling substation, whereby calls from said calling station to certain of the other stations are prevented.

27. A telephone system comprising, in combination, a plurality of stations each including an impulsive device, a line interconnecting said stations, an automatic switch associated with each of said stations, each of said switches having a home position, a plurality of operating positions individually corresponding to said stations and a predetermined operating position intermediate said home position and certain of said plurality of operating positions, means responsive to the initiation of a call at one of said stations for conditioning said switches to respond to impulses transmitted from the impulsive device at the calling station, means responsive to impulses transmitted from the impulsive device at the calling station for causing said switches to operate to said predetermined position or to one of said operating positions intermediate said home position and said predetermined position depending upon the number of impulses transmitted from the impulsive device at said calling station, and means responsive to the operation of one of said switches to said predetermined position for rendering said switches non-responsive to further impulses transmitted from the said impulsive device at said calling substation, whereby calls from said calling station to certain of the other stations are prevented.

28. A telephone system comprising, in combination, a plurality of stations each including an impulsive device, a line interconnecting said stations, an automatic switch associated with each of said stations, each of said switches having a predetermined operating position and a plurality of additional operating positions individually corresponding to said stations, means responsive to the initiation of a call at one of said stations for conditioning said switches to respond to impulses transmitted from the impulsive device at the calling station, means responsive to impulses transmitted from the impulsive device at the calling station for causing said switches to operate to the position corresponding to a called one of said stations or to said predetermined position depending upon the number of impulses transmitted from the impulsive device at said calling station, a relay operative to short-circuit the impulsive device at said calling station thereby to render

- said switches non-responsive to further operation thereof, and an operating circuit for said relay, said circuit being completed upon the operation of the switch associated with said calling station to said predetermined position, whereby calls from said calling station to certain of the other stations are prevented.
29. A telephone system comprising, in combination, a plurality of stations each including an impulsive device, a line interconnecting said stations, an automatic switch associated with each of said stations, each of said switches having a home position, a plurality of operating positions individually corresponding to said stations and a predetermined operating position intermediate said home position and certain of said plurality of operating positions, means responsive to the initiation of a call at one of said stations for conditioning said switches to respond to impulses transmitted from the impulsive device at the calling station, means responsive to impulses transmitted from the impulsive device at the calling station for causing said switches to operate to said predetermined position or to one of said operating positions intermediate said home position and said predetermined position depending upon the number of impulses transmitted from the impulsive device at said calling station, a relay operative to short-circuit the impulsive device at said calling station thereby to render said switches non-responsive to further operation thereof, and an operating circuit for said relay, said circuit being completed upon the operation of the switch associated with said calling station to said predetermined position, whereby calls from said calling station to certain of the other stations are prevented.
30. A telephone system comprising, in combination, a plurality of stations each including a telephone and an impulsive device, a line interconnecting said stations, automatic switches individually associated with said stations, each of said switches including a pulsing relay and having a plurality of operating positions individually corresponding to said stations, a normally incomplete pulsing circuit serially including said pulsing relays, means operative in response to the initiation of a call at one of said stations for connecting the telephone at the calling station to said line and for serially including the impulsive device at said calling station in said pulsing circuit, means also operative in response to the initiation of said call for completing said pulsing circuit, means including said pulsing relays operative in response to operation of the impulsive device at said calling station to interrupt said circuit for causing all of said switches to operate to the one position corresponding to a called one of said stations, and means comprising the switch associated with said called station for connecting the telephone at said called station to said line.
31. A telephone system comprising, in combination, a plurality of stations each including a telephone and an impulsive device, a line interconnecting said stations, automatic switches individually associated with said stations, each of said switches including a pulsing relay and having a normal position and a plurality of operating positions individually corresponding to said stations, a normally incomplete pulsing circuit serially including said pulsing relays, means operative in response to the initiation of a call at one of said stations for connecting the telephone at the calling station to said line and for serially including the impulsive device at said calling station in said pulsing circuit, means also operative in response to the initiation of said call for preventing the telephones at the other stations from being connected to said line in response to calls initiated at the corresponding stations and for preventing the impulsive devices at said other stations from being serially included in said pulsing circuit, means also operative in response to the initiation of said call for completing said pulsing circuit, means including said pulsing relays operative in response to the initiation of said call for connecting the telephone at said calling station to said line, means including said pulsing relays operative in response to the initiation of said call for causing all of said switches to operate to the one position corresponding to a called one of said stations, and means comprising the switch associated with said called station for connecting the telephone at said called station to said line.
32. A telephone system comprising, in combination, a plurality of stations each including a telephone and an impulsive device, a line interconnecting said stations, automatic switches individually associated with said stations, each of said switches including a pulsing relay and having a plurality of operating positions individually corresponding to said stations, a normally incomplete pulsing circuit serially including said pulsing relays, means operative in response to the initiation of a call at one of said stations for connecting the telephone at the calling station to said line and for serially including the impulsive device at said calling station in said pulsing circuit, means also operative in response to the initiation of said call for preventing the telephone at the other stations from being connected to said line in response to calls initiated at the corresponding stations and for preventing the impulsive devices at said other stations from being serially included in said pulsing circuit, means also operative in response to the initiation of said call for completing said pulsing circuit, means including said pulsing relays operative in response to the initiation of said call for connecting the telephone at the calling station to said line, means including said pulsing relays operative in response to the initiation of said call for causing all of said switches to operate to the one position corresponding to a called one of said stations, and means comprising the switch associated with said called station for connecting the telephone at said called station to said line.
33. A telephone system comprising, in combination, a plurality of stations each including a telephone and an impulsive device, a line interconnecting said stations, automatic switches individually associated with said stations, each of said switches including a pulsing relay and having a normal position and a plurality of operating positions individually corresponding to said stations, a normally incomplete pulsing circuit serially including said pulsing relays, means operative in response to the initiation of a call at one of said stations for connecting the telephone at the calling station to said line and for serially including the impulsive device at said calling station in said pulsing circuit, means also operative in response to the initiation of said call for preventing the telephones at the other stations from being connected to said line in response to calls initiated at the corresponding stations and for preventing the impulsive devices at said other stations from being serially included in said pulsing circuit, means also operative in response to the initiation of said call for completing said pulsing circuit, means including said pulsing relays operative in response to the initiation of said call for connecting the telephone at said calling station to said line.

to operation of the impulsing device at said calling station to interrupt said circuit for causing all of said switches to operate to the one position corresponding to a called one of said stations, means comprising the switch associated with said called station for connecting the telephone at said called station to said line, means responsive to a release operation performed at said calling station for interrupting said pulsing circuit, thereby to cause said switches to be restored to normal, and means for maintaining said pulsing circuit interrupted for a predetermined time interval after said release operation is performed, thereby to insure the restoration of said switches to normal even though a second call is waiting.

34. A telephone system comprising, in combination, a plurality of stations each including a telephone and an impulsing device, a line interconnecting said stations, automatic switches individually associated with said stations, each of said switches having a home position and a plurality of operating positions individually corresponding to said stations, means operative in response to the initiation of a call at one of said stations for connecting the telephone at the calling station to said line and for conditioning all of said switches to respond to operation of the impulsing device provided at the calling station, means responsive to a predetermined operation of the impulsing device provided at the calling station for causing each of said switches to operate to the one position corresponding to a called one of said stations, means including the switch associated with said called station for connecting the telephone at said called station to said line, means operative in response to a release operation performed at said calling station for causing said switches to be operated to their respective home positions, and means for preventing said switches and said line from being seized in response to the initiation of another call during the interval when said switches are being operated to their respective home positions.

45. A telephone system comprising, in combination, a plurality of stations each including a telephone and an impulsing device, a line interconnecting said stations, automatic switches individually associated with said stations, each of said switches including a pulsing relay and having a plurality of positions individually corresponding to said stations, a normally incomplete pulsing circuit serially including said pulsing relays, each of said impulsing devices including pulsing contacts adapted to be serially included in said pulsing circuit, means normally short-circuiting the pulsing contacts of each of said impulsing devices, means operative in response to the initiation of a call at one of said stations for connecting the telephone at the calling station to said line and for removing the short circuit from across the pulsing contacts of the impulsing device provided at the calling station, thereby serially to include said last-mentioned contacts in said pulsing circuit, means also operative in response to the initiation of said call for completing said pulsing circuit, means including said pulsing relays operative in response to operation of the impulsing device at said calling station to interrupt said pulsing circuit for causing all of said switches to operate to the one position corresponding to a called one of said stations, and means comprising the switch associated with said called station for connecting the telephone at said called station to said line.

56. A telephone system comprising, in combination, a plurality of stations each including a telephone and an impulsing device, a line interconnecting said stations, automatic switches individually associated with said stations, each of said switches including a pulsing relay and having a normal position and a plurality of positions individually corresponding to said stations, a normally incomplete pulsing circuit serially including said pulsing relays, each of said impulsing devices including pulsing contacts adapted to be serially included in said pulsing circuit, means normally short-circuiting the pulsing contacts of each of said impulsing devices, means operative in response to the initiation of a call at one of said stations for connecting the telephone at the calling station to said line and for removing the short circuit from across the pulsing contacts of the impulsing device provided at the calling station, thereby serially to include said last-mentioned contacts in said pulsing circuit, means also operative in response to the initiation of said call for completing said pulsing circuit, means including said pulsing relays operative in response to operation of the impulsing device at said calling station to interrupt said pulsing circuit for causing all of said switches to operate to the one position corresponding to a called one of said stations, and means comprising the switch associated with said called station for connecting the telephone at said called station to said line.

67. A telephone system comprising, in combination, a plurality of stations each including a telephone and an impulsing device, a line interconnecting said stations, automatic switches individually associated with said stations, each of said switches including a pulsing relay and having a normal position and a plurality of positions individually corresponding to said stations, a normally incomplete pulsing circuit serially including said pulsing relays, each of said impulsing devices including pulsing contacts adapted to be serially included in said pulsing circuit, means normally short-circuiting the pulsing contacts of each of said impulsing devices, means operative in response to the initiation of a call at one of said stations for connecting the telephone at the calling station to said line and for removing the short circuit from across the pulsing contacts of the impulsing device provided at the calling station, thereby serially to include said last-mentioned contacts in said pulsing circuit, means also operative in response to the initiation of said call for preventing the short circuits from being removed from across the pulsing contacts of the impulsing devices provided at the others of said stations, means also operative in response to the initiation of said call for completing said pulsing circuit, means including said pulsing relays operative in response to operation of the impulsing device at said calling station to interrupt said pulsing circuit for causing all of said switches to operate to the one position corresponding to a called one of said stations, and means comprising the switch associated with said called station for connecting the telephone at said called station to said line.

connecting the telephone at said called station to said line.

38. A telephone system comprising, in combination, a plurality of stations each including

- 5 a telephone and an impulsing device, a line interconnecting said stations, automatic switches individually associated with said stations, each of said switches including a pulsing relay and having a normal position and a plurality of positions
- 10 individually corresponding to said stations, a normally incomplete pulsing circuit serially including said pulsing relays, each of said impulsing devices including pulsing contacts adapted to be serially included in said pulsing circuit,
- 15 means normally short-circuiting the pulsing contacts of each of said impulsing devices, means operative in response to the initiation of a call at one of said stations for connecting the telephone at the calling station to said line and
- 20 for removing the short circuit from across the pulsing contacts of the impulsing device provided at the calling station, thereby serially to include said last-mentioned contacts in said pulsing circuit, means also responsive to the initiation
- 25 of said call for preventing the short circuits from being removed from across the pulsing contacts of the impulsing devices provided at the others of said stations, means also operative in response to the initiation of said call for completing
- 30 said pulsing circuit, means including said pulsing relays operative in response to operation of the impulsing device at said calling station to interrupt said pulsing circuit for causing all of said switches to operate to the one position corresponding to a called one of said stations, means comprising the switch associated with said called station for connecting the telephone at said called station to said line, means responsive to a release operation performed at said calling station for interrupting said pulsing circuit, thereby to cause said switches to be restored to normal, and means for maintaining said pulsing circuit interrupted for a predetermined time interval after said release operation is performed, thereby
- 45 to insure the restoration of said switches to normal even though a second call is waiting.

39. A telephone system comprising, in combination, a plurality of stations each including a telephone and an impulsing device, a line inter-

- 50 connecting said stations, automatic switches individually associated with said stations, each of said switches including a pulsing relay and having a plurality of positions individually corresponding to said stations, a normally incomplete pulsing circuit serially including said pulsing relays, each of said impulsing devices including pulsing contacts adapted to be serially included in said pulsing circuit, a plurality of additional relays individually associated with said stations,
- 55 each of said additional relays including contacts for connecting the telephone of the associated station to said line and contacts normally short-circuiting the pulsing contacts of the impulsing device provided at the associated station, a com-
- 60 mon circuit for energizing said additional relays, said common circuit being so connected and arranged that when one of said additional relays operates the others of said additional relays are short-circuited in response to the initiation of
- 65 calls at the respective associated stations, means operative in response to the initiation of a call at one of said stations for causing the operation of the additional relay associated with the calling station, whereby the telephone at the calling station is connected to said line and the pulsing

contacts of the impulsing device provided at the calling station are serially included in said pulsing circuit, means also operative in response to the initiation of said call for completing said pulsing circuit, means including said pulsing relays operative in response to operation of the impulsing device at said calling station to interrupt said pulsing circuit for causing all of said switches to operate to the one position corresponding to a called one of said stations, and means comprising the switch associated with said called station for connecting the telephone at said called station to said line.

40. A telephone system comprising, in combination, a plurality of stations each including a

- 15 telephone and an impulsing device, a line interconnecting said stations, automatic switches individually associated with said stations, each of said switches including a pulsing relay and having a normal position and a plurality of positions
- 20 individually corresponding to said stations, a normally incomplete pulsing circuit serially including said pulsing relays, each of said impulsing devices including pulsing contacts adapted to be serially included in said pulsing circuit, a plurality of additional relays individually associated with said stations, each of said additional relays including contacts for connecting the telephone of the associated station to said line and contacts normally short-circuiting the pulsing contacts of
- 25 the impulsing device provided at the associated station, a common circuit for energizing said additional relays, said common circuit being so connected and arranged that when one of said additional relays operates the others of said additional relays are short-circuited in response to the initiation of calls at the respective associated stations, means operative in response to the initiation of a call at one of said stations for causing the operation of the additional relay associated with the calling station, whereby the telephone at the calling station is connected to said line and the pulsing contacts of the impulsing device provided at the calling station are serially included in said pulsing circuit, means also operative in response to the initiation of said call for completing said pulsing circuit, means including said pulsing relays operative in response to operation of the impulsing device at said calling station to interrupt said pulsing circuit for causing all of said switches to operate to the one position corresponding to a called one of said stations, means comprising the switch associated with said called station for connecting the telephone at said called station to said line, means responsive to a release operation performed at said calling station for interrupting said pulsing circuit, thereby to cause said switches to be restored to normal, and means for maintaining said pulsing circuit interrupted for a predetermined time interval after said release operation is performed, thereby to insure the restoration of said switches to normal even though a second call is waiting.

41. A telephone system comprising, in combination, a plurality of stations each including a

- 15 telephone and an impulsing device, a line interconnecting said stations, automatic switches individually associated with said stations, each of said switches having a plurality of operating positions individually corresponding to said stations, means operative in response to the initiation of a call at one of said stations for connecting the telephone at the calling station to said line and for conditioning all of said switches to

5 operate in response to operation of the impulsing device provided at the calling station, means responsive to a predetermined operation of the impulsing device provided at the calling station for causing each of said switches to operate to the one position corresponding to a called one of said stations, means including the switch associated with the called station for connecting the telephone at the called station to said line, an
10 additional telephone station individually asso-

ciated with one of said switches, said additional station also including a telephone and an impulsing device, and means responsive to the initiation of a call at said additional station for connecting the telephone at said additional station to said line and for conditioning said switches to respond to operation of the impulsing device provided at said additional station. 5

EDWARD S. PETERSON. 10
